WITNESS

UNITED STATES PATENT OFFICE

ADOLPH LEVENSON, OF LONG ISLAND CITY, NEW YORK

GARMENT WEIGHT

Application filed February 1, 1929. Serial No. 336,705.

This invention relates to a garment weight for holding parts of a garment in proper position, and while the invention may be used with various kinds of garments and the like, it is more particularly designed for use with a soft collar for holding the points at the front of the collar in proper position.

The general object of the invention is to provide a weighted body having pins connected thereto in such a manner that the body can be easily and quickly attached to a garment or detached therefrom, with the parts so constructed and arranged that the device will be entirely hidden by the part of the garment to which it is attached and the parts will not form wrinkles or otherwise mark the garment in any manner.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:—

Figure 1 is a front view of a lined collar, showing the invention in use.

Figure 2 is a fragmentary view of the rear of an unlined collar, with the invention applied thereto.

Figure 3 is a rear view of the device.

Figure 4 is a section on line 4—4 of Figure 3.

Figure 5 is a detail sectional view, showing how the pin is attached to the spring member.

Figure 6 is a section on line 6—6 of Figure 5.

Figure 7 is a fragmentary rear view, showing the pin attached to the spring member.

Figure 8 is a transverse sectional view, showing how the double pin is connected with the weight.

Figure 9 is a perspective view of this double pin.

Figure 10 is a perspective view of portion of the spring member.

Figure 11 is a rear view, showing a modification.

Figure 12 is a section on line 12—12 of Figure 11.

Figure 13 is a view of the pin used in the 55 modification.

Figure 14 is a sectional view showing a further modification.

In these drawings, the numeral 1 indicates a body formed of heavy material so that it 60 forms a weight, this body being formed with a substantially flat rear face and a rounded front face and I prefer to form the body of elongated shape, as shown. A spring member 2 of elongated shape has one end fitting in a 65 recess 3 formed in the flat face of the body, this spring member being attached to the body in any suitable manner, though I prefer to form the inner end of the member with a rightangle extension 4 having recesses 70 5 in its side edges and to form a square hole 6 in the member adjacent its inner end, whereby the body, when cast, will attach itself to the spring member as the part 4 will be embedded in the body and some of the material 75 from which the body is formed will enter the opening 6, as shown in Figures 3 and 4. If desired, the spring member can be also attached to the body through means of rivets or the like, as shown at 7.

A pin 8 is attached to the outer end of the spring member and extends beyond the same and I prefer to attach the pin to the member by means of a rivet 9 which extends through an eye 10 formed on the end of the pin and 85 then the head of the rivet is upset over the eye, as shown at 11. The hole in the spring member through which the rivet passes is preferably of square formation so that the rivet is held against turning movement therein.

A double or U-shaped pin 12 has its bight portion turned at rightangles and embedded in the body, with the limbs of the double pin projecting beyond that end of the body which 95 is opposite to that to which the spring member is attached. The flat face of the body is formed with the grooves 13 to receive portions of the limbs, the grooves extending beyond the bent portions of the limbs, as shown 100

at 13', and a recess 14 communicates with each groove. These recesses facilitate bending of the limbs, as a pointed member may be placed in the recess and the adjacent part 5 of the groove and the pin bent over the same, it being understood that the double pin has its limbs bent after the body is formed around the bight portion thereof.

From the foregoing, it will be seen that the 10 double pin and the pin 8 constitute means whereby the device can be easily and quickly attached to part of a garment and detached therefrom, so that the device can be readily removed from the garment when the same is 15 to be laundered, after which the device may be placed on another garment. The double pin is pressed into a part of the garment first and then the spring member is bent and the pin 8 pressed into the garment. Thus the 20 device can be attached to a garment without causing wrinkles or marks and the device will snugly fit the rear part of the garment to which it is attached.

Of course, a single pin can be used instead 25 of the double pin, though the use of the double pin is preferable and the spring member can be formed of any resilient material, though I prefer to make this member of spring steel. This spring member has its 30 outer face flush with the rear face of the body, due to the placing of the inner end of the member in the recess 3.

When the device is used with a lined collar, as shown in Figure 1, the double pin 35 12 is passed through the lining adjacent the corner of the point, with the body and spring member extending diagonally upwardly and then the spring member is bent and the pin 8 passed through the lining. Thus the entire 40 device is hidden from view and it will hold the point of the collar in proper position and will prevent the point from turning upwardly or becoming wrinkled. The walls of the grooves 13 and the portions of the limbs 45 of the pin which pass through the grooves form locking means for the fabric of the garment which enter the grooves and the extensions 13' of the grooves prevent wrinkling 50 of the fabric as the fabric can gradually pass from the grooves through these extensions. The edges of the body are slightly beveled or rounded at the rear face to prevent the body from marking a garment and I form the flat face with an enlargement 15 adjacent one 55 side thereof so that the device can be used with an unlined collar, as shown in Figure 2. As shown in this figure, the double point is placed in the side hem 16 of the collar, with the body and spring extending substantially 60 parallel with the lower edge of the collar and with the spring 8 passing into the bottom hem 17. The enlargement 15 fits in the space formed by the hems so that portions of the flat face of the body rest upon portions of the 65 hems, with the face of the enlargement rest-

ing upon a portion of the rear face of the collar. Thus the device may be used with either lined or unlined collars of the soft type.

In the modification, the body 1' is of substantially the same shape as the body of the first form, though the spring member is eliminated, and a pair of pins 18 and 19 are used to connect the body with the garment. The pin 18 extends diagonally across the rear face 75 of the body and slightly projects from a side edge of the body, while the pin 19 projects from one end of the body adjacent the opposite side edge thereof. These pins are arranged in grooves, as in the first form of 80 the device, the grooves being associated with recesses and extensions, as before described.

I prefer to form the pins 18 and 19 of one piece of material, as shown in Figures 11 and 13, with the offset part 20 embedded in the 85 body. This body is also formed with the enlargement 15' so that it may be used with an unlined collar, and Figure 11 shows one end of the flat face of the body beveled, as at 21, thus preventing the body from marking 90 the garment. I also prefer to make the lower end of the body of such a form that this end will be heavier than the other end.

The arrangement of the pins in the modified form of the device will enable them to 95 be easily passed through the lining of a collar or other garment or into the hems of an unlined collar.

In the modification shown in Figure 14, the outer end of the spring member 2' is grooved, 100 as at 2'', under the pin 8'. This groove, with the pin, acts as locking means for the fabric and it also acts with the pin to prevent movement of the device when attached to the garment.

It is thought from the foregoing description that the advantages and novel features 105 of the invention will be readily apparent.

It is to be understood that changes may be made in the construction and in the combination and arrangement of the several parts, provided that such changes fall within the scope of the appended claims.

What I claim is:

1. A garment weight comprising a body 115 formed of heavy material and formed with a substantially flat face which is provided with a groove and a pin having a portion connected with the body, with the major portion of the pin passing through the groove, 120 whereby the fabric of the garment penetrated by the pin will be locked between the walls of the groove and the pin.

2. A garment weight comprising a body 125 formed of heavy material and formed with a substantially flat face which is provided with a groove and a pin having a portion connected with the body, with the major portion of the pin passing through the groove, where- 130 by the fabric of the garment penetrated by

the pin will be locked between the walls of the groove and the pin, the groove extending beyond the point of connection of the pin with the body to prevent wrinkling of the fabric passing from the groove and one wall of the groove having a recess therein to facilitate bending of the pin by a tool.

5. A garment weight comprising a body formed of heavy material and having one face flat, a spring strip having one end fastened to one end of said flat face with the outer face of the strip flush with said flat face, a pin connected with the outer end of the strip and a pin connected with the opposite end of the flat face of the body.

10. A garment weight comprising a body formed of heavy material and having one face flat, a spring strip having one end connected with one end of the flat face of the body, a pin connected with the outer end of the strip, a double pin connected with the opposite end of the flat face of the body, said body having grooves therein through which the limbs of the double pin pass, said grooves 25 and limbs forming means for locking the fabric to the body.

15. A garment weight comprising a body formed of heavy material and having one face flat, an enlargement on one side of the 20 said face, a spring member, means whereby one end of said member will be connected to one end of the flat face when the body is cast on the member, a pin connected with the outer end of the spring member and a double 25 pin connected with the opposite end of the flat face, said face having grooves therein for receiving the major portions of the limbs of the pin.

In testimony whereof I affix my signature.
ADOLPH LEVENSON.
